(57) **CLAIM**

The ornamental design for a base of magnetic component, as shown and described.

DESCRIPTION

FIG. 1 is a perspective view of a base of magnetic component showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dot-and-dash broken lines shown in FIGS. 1 and 3 denote the boundary of the claim and form no part of the claimed design.

The broken line portions in the drawing views are included to show unclaimed subject matter only and form no part of the claimed design.
